UNITED STATES PATENT OFFICE.

JOHN DE CARLO, OF BROOKLYN, NEW YORK.

CAMPHOR HOLDER FOR PIANOS.

1,407,788.

Specification of Letters Patent. Patented Feb. 28, 1922.

Application filed March 7, 1916, Serial No. 82,698. Renewed August 30, 1921. Serial No. 497,044.

To all whom it may concern:

Be it known that I, JOHN DE CARLO, a citizen of the United States, residing at Brooklyn, in the county of Kings, State of 5 New York, have invented certain new and useful Improvements in Camphor Holders for Pianos; and I do hereby declare the following to be a full, clear, and exact description of the invention, such as will enable others skilled in the art to which it 10 appertains to make and use the same.

The present invention is directed to improvements in camphor holders for pianos, and has for its object to so construct a device 15 of this character that the same can be easily and quickly attached to the backboard of an upright piano, and when in place the fumes from the camphor will protect the felt from moths.

20 A further object of the invention is to provide a holder of this character so constructed that the camphor can be readily removed after losing its strength and a new piece substituted.

25 It has been the usual practice to drop a number of moth balls into the piano case, but this is objectionable, since it frequently occurs that the moth balls will become lodged under the keys or between the wires, 30 thus affecting the operation of the piano.

Other means have been resorted to such as suspending a bag within the piano case filled with moth balls or camphor, but this is also objectionable since mice will gnaw the 35 bag, thus permitting the contents to drop and affect the operation of the piano.

With these and other objects in view, this invention resides in the novel features of construction, formation, combination and 40 arrangement of parts to be hereinafter more fully described, claimed and illustrated in the accompanying drawing, in which:—

Figure 1 is a fragmentary view of a back-

board of a piano, showing the holder in place.

Figure 2 is a sectional view on line 2—2 of Figure 1.

Referring to the drawing 1 indicates the backboard of an upright piano, and 2 one of the tuning pins and to which the holder 50 3 is adapted to be attached so as to suspend the same properly within the piano case.

The holder 3 consists of a casing preferably rectangular in shape and has its sides 4 and front 5 provided with a plurality of 55 perforations 6, whereby the fumes from the camphor block 7 may escape so as to permeate the felt to prevent ravage thereof by moths.

The holder 3 is provided with a top 8 60 which can be readily removed when it is desired to place in the holder a new block of camphor.

To the back 9 of the holder is connected a horizontally disposed tube 10 which is 65 adapted to engage one of the tuning pins 2 so as to properly hold the device in place. The tube 10 is split, as at 11, whereby the same will expand when forced over the pin 2, and frictionally grip the same, thereby 70 holding the device firmly in place.

What is claimed is:—

A camphor holder for pianos comprising a perforated container, and a metal tube projecting rigidly from its back and split 75 whereby it is adapted to frictionally engage over a tuning pin, the container being of such shape as to be held thereby continuously out of contact with other parts of the piano.

In testimony whereof, I affix my signature, in the presence of two witnesses.

JOHN DE CARLO.
